WALL CONSTRUCTION

Filed March 5, 1928

HUBERT GOODSON ALFORD,
INVENTOR.

BY *Harold C. Shipman*
ATTORNEY.

UNITED STATES PATENT OFFICE

HUBERT GOODSON ALFORD, OF SASKATOON, SASKATCHEWAN, CANADA

WALL CONSTRUCTION

Application filed March 5, 1928, Serial No. 259,254, and in Canada June 20, 1927.

This invention relates to wall constructions and particularly to the blocks used in constructing the wall and the method of reinforcement between said blocks.

5 The principal object of my invention is to provide a wall composed of blocks, each block composing two pressed units held in spaced relation to each other by angle braces, having turned back end portions imbedded in 10 the respective units.

A further object is to provide suitable grooves in the outer circumference of the units forming the blocks of my wall, in which grooves reinforcement rods may be imbedded between the block units during the building 15 of the wall.

With the foregoing and other objects in view, as will appear as the description proceeds, the invention consists of the novel construction, combination and arrangement of co-operating elements as hereinafter more specifically set forth, claimed and shown in the accompanying drawings forming a part 20 of the present application, in which:

25 Fig. 1 is a perspective view of the preferred embodiment of my invention, part being broken away to more clearly show the one end of one of the angle braces.

Fig. 2 is an enlarged perspective view of 30 the preferred embodiment of my angle braces.

Like numerals of reference designate corresponding parts throughout the different views.

35 I am well aware that at the present time, many different compositions are used for making building blocks and I do not wish to limit this application to any particular composition, as any of the preferred compositions for manufacturing building blocks 40 might be used for manufacturing the units composing the preferred embodiment of my invention.

45 Each block is composed of two separately formed units 3 and 4. When I say separately formed units, I do not wish to intimate that the units 3 and 4 might not be pressed at the same operation as no doubt a method would be devised wherein two units will be 50 pressed at the same time. What I wish to

imply is that the units are not integral. 5 is angle braces with one end imbedded in each of the units 3 and 4. Preferably, I provide two of such braces between each pair of units, which braces will be suitably spaced apart 55 and preferably the upright portion of each of said angle braces is upright in parallel relation to the ends of the units, while the horizontal portion of the angle braces 5 is parallel to the top and bottom of the units. 60 Each end of these braces 5 are split along the line of bending, for a slight distance inwardly. Each end portion thus formed is bent at an angle, preferably at right angles to its main portion of the angle brace. In 65 Fig. 2 it will be noted that these end portions 6 and 7 are directed at right angles to each other and when imbedded in this position in the units 3 and 4, they provide a very strong and durable connecting brace for holding 70 these units in spaced alignment parallel with each other.

Around the outer edges of the units 3 and 4, I provide a groove 8, running along the top, bottom and opposite ends. This groove 75 may be used for effecting greater binding between the units when mortar or other binding composition is used when building the wall. This groove may also be used for imbedding rods 9 between rows of blocks. As 80 shown in Fig. 1, the rods 9 overlap the end joints between the meeting ends of the blocks and thus provide a very strong reinforced joint. In this particular construction, with the rods 9, mortar is filled in between the 85 ends of the respective blocks. If found desirable, the ends of the rods might be turned at right angles to the main portion thereof, so that one end as at 10 will protrude upwardly between the ends of two of the units in one row of blocks, while the opposite end 11, turned in an opposite direction, will protrude downwardly between the ends of two of the units in the row of blocks immediately beneath.

90 Any desirable kind of filler may be filled in between the units, such as mineral wool, dry shavings or other such insulating material.

The ordinary brick, hollow tile or cement 95

block, as are in common use, do not provide a warm wall. In all of them, there is a heavy section of conducting material which carries the cold from the outer part of the wall to the inner part. In my block, I provide very light but strong braces 5 of a different material intermediate the units 3 and 4 and therefore I contend that a much warmer wall may be constructed from my blocks.

The foregoing specification and annexed drawings disclose the preferred embodiment of my invention, but it is to be understood that minor changes may be resorted to in the commercial adaptation of my invention without departing from the scope of the invention as hereinafter claimed.

What I claim as new is:

A building block consisting of spaced wall units; spaced tie braces of angle-iron formation between said wall units; the opposite ends of the respective flanges of said braces being bent outwardly substantially in parallel alignment with each other; one set of such ends being imbedded in horizontal relationship in said units and the other set of such ends being imbedded in vertical relationship in said units.

In testimony whereof I affix my signature.

HUBERT GOODSON ALFORD.
